UNITED STATES PATENT OFFICE.

CHARLES A. STEWART, OF ANDOVER, MASSACHUSETTS.

SHOE-LINING.

1,223,297.

Specification of Letters Patent. Patented Apr. 17, 1917.

Application filed December 27, 1915. Serial No. 68,731.

To all whom it may concern:

Be it known that I, CHARLES A. STEWART, of Andover, in the county of Essex and State of Massachusetts, a citizen of the 5 United States, have invented a new and useful Improvement in Shoe-Linings, of which the following is a full, clear, and exact description, reference being had to the accompanying drawings, forming a part of this 10 specification, in explaining its nature.

The present invention relates to an improvement in shoe linings and especially to those made of cloth or leather or other fibrous material.

15 My invention has for its object the correction of a very common fault in a shoe lining, and I refer to the tendency of the lining to wear out in the back part of the shoe above the heel, or where the heel of the 20 wearer rubs against the lining. Not only is this a difficulty in shoes that have been worn for some time but often new shoes which show practically no signs of wear in other respects will soon show wear at this 25 point. The defect is a serious one presenting not only an unsightly appearance but also wear upon the stockings and discomfort to the wearer. In so far as I am aware this difficulty, although so apparent and so common, has never been corrected as it exists 30 in all shoes made at the present time.

It occurred to me that if the lining was saturated or coated with some material which would have the effect of hardening 35 and toughening it, making its fabric so that it will not be injured by the moisture of perspiration, and giving said portion of the lining an enamel-like, smooth wearing surface to reduce friction, beneficial results 40 might be obtained, and upon experiment very satisfactory results were obtained, even beyond my expectations.

A better understanding of the invention can be obtained by reference to the drawing 45 in which the figure represents a plan of a portion of a shoe lining embodying my invention.

Referring to the drawings:—

That portion 1 of the lining shown is that 50 particular part which lies in the back of the shoe directly above the heel and which covers the counter of the shoe, 2 indicating that part or edge of the lining which is attached to the sole at the heel, and 3 the back stitching 55 where the two parts of the lining are sewed together. 4 is portion of the lining

treated in accordance with my invention and is that part against which the heel of the foot normally has contact during walking. The treated portion 4 does not necessarily 60 have the form indicated, nor need the lining be treated to the extent indicated although I prefer the lining be treated from the heel to a point a little above the top edge of the counter and well around to the right and 65 left.

The lining is treated by applying to it some material or substance that will impart to the lining the characteristics above referred to, and I have found the following 70 composition to be exceedingly good in this connection, viz: a composition of white shellac and zinc oxid in the proportionate parts of 1 gallon shellac to 1 pound oxid. The application is made by a brush or may be 75 made in any other suitable manner and may be made before or after the lining is applied to the shoe, although preferably the application is made before the lining is placed in the shoe.

80 After application the composition dries very quickly leaving that portion of the lining treated not only hardened and toughened as regards its wearing properties, but making its fabric so that it will not be injured by the moisture of perspiration and imparting to said portion of the lining an enamel-like, smooth wearing surface which will soon wear very smooth reducing friction to a minimum, and which cannot be 85 easily worn through or cracked.

85 One application of the material is all that is necessary although I prefer two or even more applications if the lining is of heavy rough substance for it will sooner wear 90 smooth. Of course repeated applications of the material might give the lining an initial smooth enameled surface, but this is not necessary.

95 Having thus fully described my invention, I claim and desire to secure by Letters Patent of the United States:—

1. A shoe lining having applied to that portion thereof which comes at the rear portion of the shoe, and which covers the counter, a layer of a solidified, smooth-wearing, wear-resistant material, on the side forming the inside of the shoe, whereby the said portion of said lining is rendered more 105 wear-resisting.

110 2. A shoe lining having applied to that portion only thereof which comes at the

rear portion of the shoe, and which covers the counter, a layer of a solidified, smooth-wearing, wear-resistant material, on the side forming the inside of the shoe, whereby the 5 said portion of said lining is rendered more wear-resisting, and whereby a smooth inner surface is presented in that portion of the shoe above the heel.

3. A shoe lining having applied to that 10 portion thereof which comes at the rear portion of the shoe, and which covers the counter, a layer of a solidified, smooth-wearing, wear-resistant material, on the side forming the inside of the shoe, said material

being capable of reducing the moisture-absorbing property of said lining, whereby the said portion of said lining is rendered more wear-resisting. 15

4. A fabric shoe lining having applied to that portion thereof which comes at the rear portion of the shoe, and which covers the counter, a layer of a solidified, smooth-wearing, wear-resistant material, on the side forming the inside of the shoe, whereby the 20 said portion of said lining is rendered more 25 wear-resisting.

CHARLES A. STEWART.
